DESIGN FOR A LADY'S STOCKING

William G. Bley, Bustleton, Pa., assignor to William G. Bley and Richard C. Spurgeon, co-partners trading as Bley & Spurgeon, Philadelphia, Pa.

Application November 20, 1947, Serial No. 142,696

Term of patent 14 years

(Cl. D47—7)

To all whom it may concern:

Be it known that I, William G. Bley, a citizen of the United States of America, residing at Bustleton, in the county of Philadelphia and State of Pennsylvania, have invented a new, original, and ornamental Design for a Lady's Stocking, of which the following is a specification, reference being had to the accompanying drawings, forming part thereof.

Fig. 1 of the drawings is a perspective view of a lady's stocking from one side.

Fig. 2 is a perspective view of the front of the stocking.

I claim:

The ornamental design for a lady's stocking, as shown.

WILLIAM G. BLEY.
